UNITED STATES PATENT OFFICE.

FRED C. CAMERON, OF CHICAGO, ILLINOIS, AND JOHN McMULLEN, OF BUFFALO, NEW YORK, ASSIGNORS TO UNION METAL PRODUCTS COMPANY, OF CHICAGO, ILLINOIS, A CORPORATION OF DELAWARE.

DOOR-POST FOR CARS.

1,244,583.

Specification of Letters Patent. Patented Oct. 30, 1917.

Application filed April 3, 1916. Serial No. 88,690.

To all whom it may concern:

Be it known that we, FRED C. CAMERON and JOHN McMULLEN, citizens of the United States, residing at Chicago, in the county of 5 Cook and State of Illinois, and at Buffalo, in the county of Erie and State of New York, respectively, have invented new and useful Improvements in Door-Posts for Cars, of which the following is a full, clear, 10 and exact description.

Our invention relates to movable door posts for railroad cars, and particularly to freight cars having door openings exceeding the width of the standard sliding car 15 doors, and employing, in addition to the standard doors, supplemental doors to close them.

The object of our invention is to provide a vertically reciprocable door post of novel 20 construction which can be easily lifted and thereby unlocked to permit it to be moved out of its operative position and swung up under the roof of the car and secured in this raised position so as not to interfere 25 with the loading or unloading of the car. This we accomplish by the means herein-after fully described, and as particularly pointed out in the claims.

In the drawings:

30 Figure 1 is a side elevation of the broken away portion of a freight car embodying our invention.

Fig. 2 is a horizontal section thereof drawn to a larger scale.

35 Fig. 3 is a transverse vertical section of one side of said freight car taken on dotted line 3—3, Fig. 1, and drawn to a larger scale.

Fig. 4 is a longitudinal vertical section 40 of the same taken on dotted line 4—4, Fig. 3, looking in the direction indicated by the arrows.

Fig. 5 is a horizontal section taken on dotted line 5—5, Fig. 3, looking in the direction 45 indicated by the arrows.

Referring to the drawings, A represents the floor of a car; B the side-wall thereof; C the roof of the same, and D the door opening of greater width to permit the car to 50 be loaded with large freight. The side-walls B are provided with the usual superposed plate E, which has a suitable Z-bar e secured thereto the vertical web of which laps against the outer side of said plate, and

the upper flange of which laps over the top 55 of the same, and the lower flange of which projects outward over the doorway. This Z-bar has an angle d secured to the outer surface of the web thereof, and its lower leg projects beyond the lower flange of said 60 Z-bar and overhangs the doorway, substantially as shown in the drawings.

The car is provided with the usual car-line e for the support of roof C, and with a fascia b the lower portion of which overlaps the bolts that secure the Z-bar, and angle d to plate E.

Our improved door-post is situated, preferably, nearer one side of the doorway than the other, and the sill-plate 4 of said doorway and the decking or flooring A are recessed vertically to one side of the vertical plane of this door-post and said recess is, preferably, lined with a metal socket 5. The door-post 6 consists, preferably, of a suitable channel-beam which extends from its lower end slightly above the plane of the floor, to say, a foot of the top of the door-opening, when in its operative position, and its lower cast iron heel 7 secured to the side 80 of the web thereof, opposite its flanges by means of an attaching-plate 8, which is riveted to said web and projects down below the lower end of the post and is adapted to enter socket 5.

The upper end of post 6 enters a rectangular pendent sleeve 9, and the upper end of this sleeve terminates near the top of the doorway and is provided with knuckles 10, 10 projecting upward and sidewise from its 90 upper closed end that are pivoted upon a transverse shaft 12. The outer end of this shaft is suitably secured in a lug 13 projecting down from the outer end of a horizontal attaching-plate forming an extension 95 14 of the flanged lower edge of the horizontal arm 15 of a bracket which is secured by riveting or otherwise to the inner side and to the recessed underside of plate E. The arm 15 of said bracket projects laterally 100 in toward the center of the car, and its inner end has a downwardly turned lug 16 in which the inner end of shaft 12 is secured in any manner so as to prevent its having longitudinal movement.

The broad side of pendent sleeve 9 has a longitudinally elongated slot 18 therein, and a pin 19 projecting laterally from the web

of the post midway between its flanges out through this slot and out through a longitudinally elongated slot 20 in a rocking-bar 21, which latter is fulcrumed at its center of length to a pivotal stud 22 made integral with and projecting from sleeve 9 at a suitable point alongside of slot 18. The branch of this rocking-bar, opposite that engaged by pin 19, has a corresponding longitudinally elongated slot 23 therein, and this slot is engaged by a pin projecting from the lower end of a vertically disposed reciprocable bolt 25. This bolt extends vertically up through a guide-lug 31 projecting from the narrow side or edge of sleeve 9, and when the post is in its vertical operative position the bolt will be shot upward and engage a lug 27 depending from extension 14 of bracket 15 in the vertical plane of the inner face of plate E.

In its operative position, heel 7 of the post will rest in socket 5, the upper end of the post will be at the lower limit of its position in sleeve 9, and the upper reciprocable bolt 25 will engage lug 27. In order to move said post out of the way, when it is desired to use the full width of the doorway for the introduction into the car of large freight, a handle 28 that consists of a horizontal bolt connecting and bridging the space between the flanges of the post nearer its lower end, is grasped and the post lifted vertically until stationary bolt 7 is lifted out of socket 5. This vertical movement of the post, through the medium of rocking-bar 21, causes bolts 25 to withdraw from engagement with lug 27 and permits the said post to be swung on shaft 12 into or toward a horizontal position, and then moved laterally on said shaft from the doorway, and when it has reached this position to be engaged by a hook (not shown) secured to and depending from one of the car-lines of the car, or other part of the roof structure.

When the post has been lowered and secured in its vertical position in the manner hereinbefore stated, doors α and α' can be closed by sliding them toward each other until the opposed edges thereof strike a vertically disposed jamb-plate 32 secured to and projecting from the outwardly projecting leg of a vertically disposed angle 30, which is riveted or otherwise secured to the outer edge of the lower portion of the post, which angle constitutes the jamb for said doors. When thus closed the doors can be secured together by any suitable means.

What we claim as new is:—

60 1. A car having an enlarged doorway, and doors therefor, in combination with a vertical post the heel of which is adapted to be secured to the sill of said doorway, a sleeve pivoted at its upper end adjacent the top of said doorway in which the upper

end of said post is reciprocable; said post being adapted to be raised vertically out of said recess and swung on the pivot of said sleeve into a horizontal position, and means for retaining it in a horizontal position.

2. A car having an enlarged doorway, and doors therefor, in combination with a vertical post the heel of which is adapted to be secured to the sill of said doorway, a pendent sleeve in which the upper end of said post is reciprocable, a transverse shaft on which the upper end of said sleeve is loosely mounted; said post being movable vertically to lift its heel out of said recess and adapted to be swung upward on the axis of said shaft and moved toward the center of the car, and means for retaining it in a horizontal position.

3. A car having an enlarged doorway, and doors therefor, in combination with a vertical post the heel of which is adapted to be secured to the sill of said doorway and which has a vertically reciprocable movement and can be swung into a horizontal position from a pivotal center adjacent its upper end, an automatically reciprocable bolt for securing the upper end of the post which is withdrawn when said post is moved vertically and shot upward when said post is reciprocated downward, and means for retaining said post in its raised horizontal position.

4. A car having an enlarged doorway, and doors therefor, in combination with a vertical post the heel of which is adapted to be secured to the sill of said doorway, a sleeve pivoted at its upper end adjacent the top of said doorway in which the upper end of said post is reciprocable; said post being adapted to be raised vertically out of said recess and swung on the pivot of said sleeve into a horizontal position, an automatically reciprocable bolt slidably mounted on said sleeve and adapted to be shot downward when said post is moved vertically upward and shot upward when said post is reciprocated downward, and means for retaining it in a horizontal position.

5. A car having an enlarged doorway, and doors therefor, in combination with a vertically reciprocable post the heel of which is adapted to engage a recess in the sill of said doorway, a pendent sleeve in which the upper end of said post has telescopic movement, a transverse shaft upon which said sleeve is pivotally mounted and movable thereon toward the center of the car, a vertically reciprocable bolt, and means actuated by said post for shooting said bolt downward when it is reciprocated upward, and vice versa.

6. A car having an enlarged door opening and doors therefor, in combination with a vertically reciprocable post the heel of which is adapted to engage a recess in the

sill of said doorway, a pendent sleeve pivotally supported at its upper end in which the upper end of said post has telescopic movement, and which has a longitudinal slot therein, a pin projecting laterally from the post out through said slot, a longitudinally reciprocable bolt carried by said sleeve, a rocking-member fulcrumed mediate its ends to said sleeve and adapted to transmit the reciprocable motion of said post to said bolt.

7. A car having an enlarged door opening, and doors therefor, in combination with a vertically reciprocable door post the heel of which is adapted to engage a recess in the sill of said doorway, a pendent sleeve in which the upper end of said post has telescopic movement, a transverse shaft on which said sleeve is pivotally mounted, a transverse bracket secured above said door-

way in downwardly projecting end lugs of 20 which said shaft is secured, a lug projecting downward therefrom mediate said end lugs, a longitudinally reciprocable bolt carried by said sleeve and adapted when said post is moved vertically downward to engage said 25 medially placed lug and when said post is moved vertically downward to withdraw from engagement therewith.

In witness whereof we have hereunto set our hands this 30th day of March, 1916.

FRED C. CAMERON.
JOHN McMULLEN.
